GARTER

Max F. Ascher, Chicago, Ill.

Application September 16, 1932
Serial No. 633,442

4 Claims. (Cl. 2—240)

This invention relates to garters and fastenings therefor, and more especially to the permanent attachment of garters to socks.

The main objects of the invention are to provide an improved form of garter and structural details therefor, and means for securing the garter permanently to the upper part of a sock or stocking; to provide a combination sock and garter secured together substantially integrally and permanently, and adapted for embracing the leg well above the upper edge of the sock except at the point of fastening, as for instance to embrace the upper part of the calf; and to provide such a combination sock and garter of unitary character adapted for frequent washing as a whole.

This invention is illustrated by the accompanying drawing in which:

Figure 1 is a perspective view of a combined sock and garter in actual use.

Fig. 2 is an enlarged side elevation of the garter applied to a sock, ready for use.

Fig. 3 shows in spaced relation a greatly enlarged axial cross section of the fastener shell, the garter ends, inner plug, sock and outer plug, ready for assemblage.

Fig. 4 is similar to Fig. 3 except that the component parts have been brought together and fastened in place by flattening and so expanding the plugs in place in the shell the parts all being shown in section on the line 4—4 of Fig. 2.

Referring more in detail to the drawing, the garter 1 is secured to the upper edge part of a sock 2, by means of a fastener 3, the main body 35 of the garter being elastic and adapted to assume an inclined position extending downwardly on one side for attachment to the sock, and upwardly on the other side to embrace the upper part of the leg or calf, as at 4.

The said fastener 3 is of discoidal shape and comprises substantially a button-shaped hollow body member 5, open on one side, with overhanging edges 6, in combination with an expandable cup plug 7, adapted for setting in place 45 against the inner face of the button member to grip the garter ends 8 and 9 therebetween, and having side prongs 10 adapted for outward setting to engage under the button flanges, and a second plug 11 like plug 7 in order to hold the sock in place. Plug 11 is applied with the upper sock

fabric interposed between the two plugs, and is secured in place by expanding its arms after the parts are assembled.

The fastener body 5 is of duplex design and comprises two flattish members 12 and 13, the former having a central aperture 14 to receive the garter and sock fabric and also the plugs. These members 12 and 13 have conoidal flanges 15 and 16 respectively, the latter overlapping the former, whereby the parts 12 and 13 are secured permanently together, and the garter is held punctually to the sock, that is to say, locally or at one point.

It is to be understood that some of the details set forth may be altered or omitted without departing from the spirit of the invention as defined by the following claims.

I claim:

1. In combination, a sock and elastic band together with a fastener whereby said band is secured to the upper part of the sock, said fastener comprising a hollow shell and an expandable plug, whereby the band is secured directly to the shell, and another substantially similar plug whereby the sock is secured in the same manner over the first plug.

2. A device of the class described comprising a discoidal hollow shell apertured on one side with an overlapping flange about the opening, in combination with a pair of garter ends and part of a sock all three extending into said shell and means set in said shell to secure said members in place.

3. The method of attaching a garter to a sock, which consists in applying the ends of a garter strip to the interior of a hollow button-like shell, clamping the same in place by expanding a hollow plug therein, then applying the device to the upper edge of a sock and securing the latter in place by expanding another plug substantially within the first plug and into locking engagement with the shell member.

4. A fastener of the class described comprising a discoidal hollow shell apertured on one side, in combination with a pair of garter ends and the rim of a sock all three extending into said shell and means set in the shell aperture with the said ends and rim interposed to secure said members in place.

MAX F. ASCHER. 105
